UNITED STATES PATENT OFFICE.

JOHN FITZPATRICK, OF PARKERTON, WYOMING, ASSIGNOR, BY MESNE ASSIGNMENTS, TO THE TEXAS COMPANY, OF NEW YORK, N. Y., A CORPORATION OF DELAWARE.

WELL-PUMPING APPARATUS.

Application filed February 7, 1927. Serial No. 166,284.

This invention relates to well pumping apparatus and more particularly to an improved form of tubing bleeder.

During the pumping of a well, the well tubing is generally either partially or wholly filled with the liquid being pumped, and the liquid is retained within the tubing by means of a standing valve or the like, which is disposed at or near the bottom of the pumping apparatus. When the pumping of the well has been completed, and it is desired to withdraw the tubing, it is ordinarily necessary to pull the tubing while it is still filled with liquid. This not only imposes a considerable strain on the lifting apparatus but messes up the derrick floor.

My invention contemplates as one of its objects the provision of means for draining a well tubing in order to lighten the load which must be lifted in raising the tubing.

In a more specific aspect one of the objects of the invention is to provide a tubing bleeder or valve which normally operates to prevent any backward flow of liquid but which can be readily opened to permit quick draining of the tubing.

Other objects, features and advantages of the invention will readily appear as the description thereof proceeds.

30 In the drawing:

Figure 1 is a longitudinal sectional view through a tubing bleeder embodying my invention, showing the bleeder in closed position, and

35 Figure 2 is a view of the same tubing bleeder partially in section and drawn to an enlarged scale, showing the bleeder in open position.

40 Referring to the drawing, there is shown a portion of the lower end of the well casing 10 which at its upper end is connected in the usual manner to the well pumping apparatus. A tubular member 11 which is internally tapered throughout its length is secured to the lower end of the tubing 10 by means of a coupling member 12. An inverted L shaped slot 13 having at its upper extremity an offset portion 13' is formed in the wall of the tubular member 11. A second tubular member 14 which is externally tapered to correspond to the internal taper of the member 11 is positioned partially within the member 11 and adapted to telescope therewith. A stud 15 is secured in the wall 55 of the tubular member 14 with its extending

head projecting into the slot 13 so as to restrict the relative movement of the telescoping members.

A standing valve 16 is positioned within the bore of the tubular member 14. The lower end of the tubular member 14 which extends beyond the lower end of the member 11 is secured to a short section of tubing, such as a shoe, or as illustrated—a perforated section of pipe 17 constituting a strainer, by means of a coupling member 18.

During normal pumping operations a slight tension is maintained upon the tubing and particularly on the cooperating faces of the members 11 and 14 due to the weight of the standing valve 16 and the strainer 17, this tension being sufficient to insure a snug fit between the tapered sections 11 and 14 so as to prevent any downward leakage of liquid between these members.

When it is desired to drain the tubing prior to withdrawing it from the well the whole apparatus is lowered until the pipe section 17 rests upon the bottom of the well. The inner tubular member 14 then telescopes 80 within the member 11, leaving a space such as 19 through which the liquid in the tubing may drain out.

In order that this space may be maintained as the tubing is withdrawn from the well the casing 10 which is rigidly secured to the member 11 by the coupling 12 is rotated slightly to the right and on account of the shape of the slot 13 this slight rotary motion of the member 11 relative to the member 14 90 moves the stud 15 into the offset portion 13' of the slot, thereby locking the telescoping members in position with a fixed space between their adjacent walls. Thus as the tubing is raised to the surface by the usual lifting apparatus the entire liquid content of the tubing is drained out and flows back into the well.

Apparatus of preferred form and construction has been illustrated and described 100 for the purpose of showing one way in which the invention may be practiced, but the inventive thought upon which the invention is based is broader than this illustrative embodiment thereof and no limitations are 105 therefore intended other than those imposed by the appended claims.

What I claim is:

1. A well tubing bleeder comprising a pair 110 of tapered tubular members concentrically

disposed throughout a portion of their lengths, a standing valve disposed within the inner of the tubular members, means for normally maintaining the tubular members in close engagement to prevent leakage between their adjacent walls, and means for telescoping the tubular members to provide a space between them through which liquid in the well tubing can escape.

10 2. A well tubing bleeder comprising a pair of tapered tubular members concentrically disposed throughout a portion of their lengths, a standing valve disposed within the inner of the tubular members, means for normally maintaining the tubular members in close engagement to prevent leakage between their adjacent walls, means for telescoping the tubular members to provide a space between them through which liquid in the well tubing can escape, and means for maintaining the tubular members in spaced relation.

25 3. A well tubing bleeder comprising a pair of tapered tubular members concentrically disposed throughout a portion of their length, a standing valve disposed within the inner of the tubular members, a perforated pipe secured to the lower extended end of

the inner tubular member to maintain the adjacent walls of the members in sealing engagement, and means for telescoping the tapered members to provide a drainage space therebetween through which the liquid in the well tubing can flow back into the well.

30 4. A well tubing bleeder comprising a pair of tapered tubular members concentrically disposed throughout a portion of their lengths, the outer of said tubular members being formed with an elongated slot having an offset portion at its upper end, a stud secured to the wall of the inner tubular member with its projecting portion adapted to slide in the slot of the outer member, a standing valve disposed in the bore of the inner tubular member to prevent any back-flow of liquid therethrough to the well, and means for telescoping the tubular members to provide a space between their adjacent walls through which liquid confined in the well tubing by the standing valve can flow back to the well.

35 45 In witness whereof I have hereunto set my hand this second day of December 1926.

50 JNO. FITZPATRICK.
